UNITED STATES PATENT OFFICE.

ABNER BARON, OF NEW YORK, N. Y., ASSIGNOR TO ROYAL CARD & PAPER CO., A CORPORATION OF NEW YORK.

DESIGN FOR WRAPPING PAPER.

Application filed May 26, 1928. Serial No. 26,871 Term of patent 14 years.

To all whom it may concern:

Be it known that I, ABNER BARON, a citizen of the United States of America, and resident of the city of New York, county of New York, and State of New York, have invented a new, original, and ornamental Design for Wrapping Paper, of which the following is a specification, reference being had to the accompanying drawing, forming part thereof.

The figure is a plan view of wrapping paper, illustrating my new and ornamental design.

I claim:

The ornamental design for wrapping paper as shown.

ABNER BARON.
